UNITED STATES PATENT OFFICE.

JAMES CALLAGHAN, OF MONTREAL, QUEBEC, CANADA.

CIGARETTE-TIPPING MACHINE.

1,234,285.

Specification of Letters Patent. Patented July 24, 1917.

Application filed April 8, 1913. Serial No. 759,636.

To all whom it may concern:

Be it known that I, JAMES CALLAGHAN, a subject of the King of Great Britain, residing at the city of Montreal, in the Province of Quebec and Dominion of Canada, have invented new and useful Improvements in Cigarette-Tipping Machines, of which the following is a full, clear, and exact description.

This invention relates to improvements in cigarette tipping machines, and the object in general is to provide means for applying tips of cork or other material to cigarettes more rapidly and perfectly than heretofore possible.

The machine comprises essentially a belt onto which the cigarettes are fed from a hopper, a feeding and pasting mechanism for the tipping material, and means for applying the tipping material to the cigarettes. Coöoperating with these means are means for cutting the tipping material any suitable length, means for holding the cigarettes during tipping, and means for moving the tipping mechanism to correspond with the movement of the cigarette carrying belt.

In the drawings which illustrate the invention:—

Figure 1 is a front elevation of the machine.

Fig. 2 is a plan view of same.

Fig. 3 is a right hand end elevation.

Fig. 4 is a rear elevation of the tip feeding and pasting mechanism.

Fig. 5 is a sectional view on the line 5—5, Fig. 2, showing the tipping mechanism enlarged.

Fig. 6 is a similar section on the line 6—6, Fig. 2.

Fig. 7 is a rear elevation of the tipping mechanism on the same scale as Figs. 5 and 6.

Fig. 8 is a longitudinal section of the sleeve and cams operating the tipping mechanism.

Fig. 9 is an enlarged front elevation of a fragment of the tipping chain, showing the first step of the tipping operation.

Fig. 10 is a view similar to Fig. 9 illustrating the commencement of the second step of the tipping operation.

Fig. 11 is a view similar to Figs. 9 and 10 illustrating the commencement of the third and last step of the tipping operation.

Referring more particularly to the drawings, 11 designates a bed upon which all

the parts of the apparatus are mounted. At the ends of this bed are transversely disposed shafts 12 upon which are rigidly mounted drums 13 carrying the cigarette belt 14 and tipping belt 15. One of these shafts 12 preferably at the right hand end of the machine extends to the front of the bed, and is provided with a worm wheel 16 meshing with a worm 17 mounted on a power distributing shaft 18 arranged longitudinally at the front of the bed. This distributing shaft 18 is provided with fast and loose pulleys 19 and 20 respectively.

The cigarette carrying belt consists of a plurality of short wide links 21 pivotally connected and each provided on its upper surface with a cigarette holding groove 22. The width of the links 21 is approximately equal to the length of a cigarette, so that the cigarettes will be supported throughout their entire length and held against any relative movement by the grooves in which they lie. The cigarettes are contained in a hopper 23 mounted at the left hand end of the machine, and feed out through an opening 24 at the bottom of the hopper into the grooves of the carrying belt 14. The outlet of the hopper may be provided with a gate of any suitable form (not shown) for regulating the escape of the cigarettes.

The tipping belt 15 which is located to the front of the carrying belt is much narrower, its width being approximately equal to the length of tip which it is desired to apply. This belt is composed of links 25 of exactly the same length as the links 21 of the carrying belt, and each provided with a groove 26 in the upper surface thereof in register with the grooves 22 of the carrying belt, in order that as the cigarettes advance with the carrying belt their rear ends will be brought into contact with a stationary cam 27, and thus projected forward into the grooves of the tipping belt. The links of the tipping belt are each hollowed out under the grooves, as indicated at 28, the recesses thus formed being in communication with the grooves through a plurality of minute or capillary apertures 29. The abutting ends of the links are also cut away above their points of pivotal connection to form recesses 30, into which the tipping mechanism may be projected. At the point where the tipping operation is to be performed, the tipping belt passes over a suction box 31, the joint between the belt

and box being made as nearly fluid tight as possible, so that air will be drawn in only through the capillary apertures 29.

The tip pasting and feeding mechanism 5 is all mounted on a vertical frame 32 secured to the bed immediately in front of the tipping belt. The tipping material, which may be cork, gold or silver surfaced paper or the like, is prepared in the form 10 of a ribbon wound on a spool 33 carried by the frame 32. The ribbon of tipping material designated 34 passes downwardly from the spool under a double flanged idler roll 35 and over a similar roll 36, and under the 15 knurled pasting roll 37. This pasting roll 37 projects partly into the bottom of a paste reservoir 38, and carries the paste out of the reservoir by means of its roughened surface. After leaving the paste roll 37 the tipping 20 material passes between a pair of knurled discharge rolls 38 and 39 into a small flanged trough 40, through which it slides onto the tipping belt 15. The material is prevented from buckling or curling and escaping from 25 the trough, and is also pressed down onto the tipping belt by a gravity actuated pivot arm 41. The upper discharge roll 38 is mounted at one end of a bell-crank lever 42, the opposite end of which is connected to a 30 tensioned spring 43, which operates to press the roll 38 downwardly against the roll 39. The paste roll 37 and discharge roll 39 are provided with small chain wheels 44 and 45 respectively over which an endless chain 46 35 passes to a drive wheel 47, driven by miter gears 48 from the distributing shaft 18. It will be noted in Fig. 1 that the wheel 45 of the discharge roll is slightly smaller than the wheels 44 and 47, which are preferably 40 of equal size, so that the discharge roll will turn a trifle faster than the paste roll, and thus keep the material in tension. The gearing is also so arranged that the surface speed 45 of the discharge roll 39 is slightly greater than the surface speed of the tipping belt, so that a sufficient slackness will be maintained in the tipping material to permit of its being drawn down into the grooves of 50 the tipping belt by the suction previously described.

The tipping mechanism is mounted on a table 49 which is slidable longitudinally of the machine bed between guides 50 secured to said bed. This table is reciprocated by 55 means of a cam 51 mounted on the shaft 18 engaging a roller 52 carried by the table. Suitable springs 53 are provided to hold the table roll always against the cam. A slide 54 is mounted in guides 55 carried by 60 the table. This slide is in the form of a flat plate standing on edge and arranged to move transversely of the machine, that is, from front to back, as is clearly shown by the drawings. The table 49 is preferably 65 mounted centrally under the shaft 18 which

passes through a slot 56 formed in the slide 54. This slide is operated by a cam 57 carried by the shaft 18 and pressing against a roller 58 mounted preferably on the left hand face of the slide. Springs 59 secured 70 in tension between the slide and its guides hold the cam and roller always in contact. The throw of the cam 57 is approximately equal to the length of tip which it is desired to attach to the cigarette, or in other words, 75 to the width of the ribbon of tipping material. This slide and all the parts carried thereby are entirely out of contact with the tipping belt 15 when the slide is retracted, but when the slide is advanced the tipping 80 members project into the path of the belt and are received in the recesses 30 thereof, the table carrying the slide being at this time moved by its cam at the same speed as the belt, so that the parts do not interfere 85 with one another. At the rear end of the slide 54 is a vertically disposed slide 60 preferably arranged on the opposite side of the horizontal slide 54 from the operating cam 57, that is, on the right hand side. This 90 vertical slide 60 is operated by a lever 61 pivoted at one extremity 62 to the front end of the slide 54, and connected at the opposite extremity by a link 63 with the slide. The lever carries intermediate its extremities a 95 roller 64, which when the slide 54 is in its forward position is engaged by a cam 65 having its throw arranged in two stages concentric with the shaft 18 carrying the cam, as clearly shown in Fig. 5. From this, it 100 will be seen that the slide 60 will rise a certain distance, pause, and then rise farther and finally drop directly to its lowest position. A spring 66 is tensioned between the lever 61 and horizontal slide 54 to hold the 105 vertical slide 60 normally in its lowest position. Excess downward movement of this slide is prevented by a stop 67.

The vertical slide 60 carries an arm 68, the free end of which is provided with bifurcations 69 spaced apart sufficiently to be inserted in adjacent recesses 30 of the tipping chain, and thus embrace the hollow grooved top portion of each link carrying a cigarette. Each of these bifurcations 69 is 115 provided with a plurality of pins 70 and 71. The pins 70 mounted on the left hand bifurcation are twice the length of the pins 71 mounted on the right hand bifurcation, as will be clearly seen in Figs. 9, 10 and 11. 120 The distance from the top of the long pins 70 to the bottom of the bifurcation carrying arm is approximately equal to the depth of the recesses 30 of the tipping chain, so that the bifurcations may be projected into these 125 recesses without the pins 70 or 71 catching on the strip of tipping material lying under the top of the chain.

A shear blade 72 is rigidly mounted on the rear end of the slide 54 a short distance to 130

the left of the left bifurcation 69, so as to enter the same chain recess 30 as this bifurcation. The upper or cutting edge of this blade is at approximately the same level as the top of the pins 70. A moving shear blade 73 is provided coöperating with the fixed blade 72. This blade is mounted at the right of a vertical polygonal spindle 74, which slides in extensions 75 of the horizontal slide 54. The blade 73 is held normally elevated by means of a spring 76, compressed between the upper spindle holding extension 75 and the top of the spindle. The lower end of the spindle is provided with a pair of collars 77 between which the spindle is embraced by the bifurcated extremity 78 of a lever 79. This lever 79 is located on the left hand side of the horizontal slide 54, and is pivoted at its opposite extremity 80 from the bifurcations 78 to said slide in contra-distinction to the lever 61, which extends above the shaft. A roller 81 is mounted on the lever 79 intermediate the ends thereof and in such position that when the slide 54 is in its forward position, this roller 81 will be engaged by a cam 82 carried by the shaft 18 and mounted to the left of the cam 57. Expansion of the spring 76 holds this lever and its roller always up to position, while the blade 73 engaging beneath the slide extension 75 prevents excess upward movement.

The horizontal slide 54 is provided at its rear end with a rearwardly projecting elevated arm 83, to which a lever 84 is pivoted at its upper extremity in such a way as to oscillate longitudinally of the tipping belt. A small brush 85 is mounted on the lower end of this lever 84. The front guide supporting the slide 60 is provided with a journal 86, in which is mounted a short shaft 87 extending from front to back of the machine. This shaft carries two arms 88 and 89 rigidly connected to its opposite ends. The front arm 88 is provided at its upper extremity with a roller 90 positioned to engage the side of the cam 65 upon which a partially raised flange 91 is formed, so that the cam 65 is in reality two cams in one. The rearmost arm 89 is pivotally connected at its upper extremity with the lever 84 at a point intermediate the extremities thereof. A small spring 92 is held in tension between the arm 89 and the slide 54 so as to hold the roller 90 always against the side of the cam 65.

It will be readily understood from the preceding description that the cams 57, 65 and 82 obviously must maintain a fixed relation with the table 49, as they operate the various parts carried by the table. It will also be remembered that the table moves longitudinally of the machine bed. In order to make possible this fixed relation, these cams 57, 65 and 82 are rigidly mounted on

a sleeve 93, which is slideable longitudinally on the shaft 18, and is provided with an internally projecting fin or key 94 engaging a longitudinal slot 95 formed in the shaft 18, so that the sleeve and cams thereof may be moved longitudinally of the shaft with the movement of the table and at the same time receive rotary motion from the shaft. In order to hold the main body of the cigarettes rigidly in the grooves of the carrying belt 14 during the tipping operation, a bracket 96 is secured to the right hand end of the frame and curves around outside the carrying belt, as clearly shown in Fig. 1, and also extends over the top of the belt to a point a short distance to the left of the tipping mechanism. A pair of loose rolls 97 are revolvably mounted in this bracket, one at the free extremity thereof and the other some distance below the level of the upper horizontal surface of the carrying belt. An endless belt 98 of webbing or other suitable material passes over these rollers 97, the upper half of this belt running approximately straight between the rollers 90 while the lower half conforms to the curvature of the carrying belt, so that a constant tension is maintained in the belt 98 and it is kept constantly pressed down on the carrying belt. 95

The operation of the device has already been more or less described, but to give a more perfect understanding it may be summarized as follows:—The cigarettes are discharged from the magazine onto the carrying belt 14. Simultaneously, the tipping material feeds from the spool through the pasting device and over the top of the tipping belt 15, and moves with the belt when the belt passes over the suction box 31. The rush of air from the capillary apertures 29 draws the tipping material down to conform with the curvature of the cigarette grooves, so that the cigarettes moved forward by the cam 27 slide on top of the pasted surface of the tipping material, so that the material is pasted to approximately one-half of the cigarette's circumference. Substantially simultaneous with the forward movement of the cigarette onto the tipping belt, the horizontal slide 54 moves forward and projects the bifurcations 69 and lower shear blades 72 into the recesses 30 of the tipping belt. During this rearward movement of the slide 54, the table 49 moves the slide longitudinally of the machine to keep pace with the movement of the tipping belt. The upper shear blade 73 is now drawn down by the action of the cam 82 and coöperates with the lower blade 73 to sever a suitable length of tipping material. The vertical slide 60 rises half way, and the long pins 70 carried by the arm 68 raise the severed end of the tipping material to substantially vertical position, as shown in Fig. 10. The cam 130

flange 91 of the cam 65 operates the arm 89 to oscillate the brush lever 84, so that the brush moves to the right and presses the recently severed end of the tip along down on the cigarette, where it is held by the adhesive. The brush remains in its extreme right hand position, while the arm 68 rises to full height, so that the short pins 71 turn up the loose end of the tipping material.

5 The brush then returns to its original position and presses down the material during its return passage over the cigarette. During the oscillation of the brush, the upper shear blade remains depressed and out of the way of the brush. During the tipping operation, the table is moved toward the right hand a distance approximately equal to the length of one link of the tipping chain. The horizontal slide moves forward, the 10 shear blade rises, and the arm 68 drops, thus disengaging the entire tipping mechanism from the tipping chain. The table is then drawn back by its springs into register with the next link of the chain and the tipping 15 mechanism moved rearwardly to engage the succeeding cigarette, as just described. When the tipping operation is complete, the cigarette has been carried by the two chains beyond the influence of the suction box 31,

20 so that it is entirely free from both belts, but cannot, however, become dislodged until it passes out from under the holding belt 98 as the carrying belt passes around its right hand supporting wheel. This holding belt 25 98 keeps the cigarette pressed tightly in the grooves of the carrying belt, so that any dislodgment or independent movement during the tipping operation is absolutely prevented.

30 40 While the invention has been shown and described as equipped only with a single tipping mechanism, it is obvious that the number of tipping mechanisms may be multiplied, so that a plurality of cigarettes may 45 be simultaneously tipped in the same time as one. In such an arrangement, the drive of the carrying and tipping belts would preferably be of the variable speed type, so as to make a quick feed of the cigarettes 50 during the return movement of the table. In a single machine various lengths of cigarettes may be handled by substituting different sizes of magazines and carrying belts. The width of tipping material used may also be 55 varied by substituting rolls and carrying spool of the proper dimension. Except in very extreme cases, it will not be necessary to change the parts of the tipping mechanism as a single size of these will operate 60 equally well with all the widths of tip usually employed. A great advantage of this device is that the capacity of the apparatus is increased without shortening the length of time occupied in tipping each cigarette by 65 reason of the travel of the tipping appa-

ratus with the chain, so that a high speed is obtained without sacrificing any perfection of result.

Having thus described my invention, what I claim is:

1. In a cigarette tipping machine, the combination with a tip material pasting and feeding device of a belt adapted to support cigarettes during tipping operation positioned to receive pasted tip material from said pasting mechanism, said belt comprising a plurality of pivotally connected links each having the central portion higher than the ends whereby pockets will be formed between the links, said central link portions being grooved on the upper surface in conformity with the circumferential curvature of a cigarette and hollowed out from beneath capillary ducts connecting the hollow interior of the link with the bottom of the groove thereof, and a vacuum box positioned to be engaged by the underside of said belt and arranged to draw down the tip material into conformity with the grooves by suction through the ducts in readiness to receive the cigarettes.

2. In a cigarette tipping machine, a continuously moving cigarette support having cigarette receiving grooves and pockets alternated with said grooves, tip cutting shears movable into the support pockets, tip wrapping means, certain portions of said wrapping means being movable into the support pockets, a shaft, a slide carrying said shears and tip wrapping means, a guide for the slide, a cam on the shaft operating the slide to move the shears and wrapping means into the support pockets, a sliding table carrying the guide, a cam on said shaft adapted to move the table with the cigarette support during engagement of the shears, and certain portions of the wrapping means in the support pockets, retracting means for said slide, and retracting means for the table.

3. In a cigarette tipping machine, a continuously moving cigarette support having cigarette receiving grooves and pockets alternated with said grooves, means for feeding pasted tip material over said grooves, means for feeding cigarettes onto the tip material in said grooves, tip cutting shears movable into the support pockets, tip wrapping means, a shaft, a slide carrying said shears and tip wrapping means, a guide for the slide, a cam on the shaft operating the slide to move the shears and certain portions of the wrapping means into the support pockets, a sliding table carrying the guide, a cam on said shaft adapted to move the table with the cigarette support during engagement of the shears and wrapping means in the support pockets, retracting means for said slide, and retracting means for the table.

4. In a cigarette tipping machine, a continuously moving pocketed cigarette support, tip cutting means movable into and out of said support pockets, tip wrapping means, a slide carrying said cutting and wrapping means resiliently held against movement toward the cigarette support, a shaft, a slidable sleeve thereon held against revolution independently of the shaft, a 10 cam on said sleeve operating the slide toward and away from the cigarette support, a guide for said slide, a table carrying the guide and resiliently held against movement with the cigarette support, a cam on 15 the shaft adapted to move the table and slide thereon with the cigarette support during engagement of the cutting device in the support pockets and in the reverse direction during withdrawal of said cutting device 20 and means for moving said sleeve along the shaft with the movement of the table.

5. In a cigarette tipping machine, a continuously moving pocketed cigarette support, a table movable parallel with said support, a slide carried by the table movable toward and away from the cigarette support, tip cutting and tip wrapping mechanism mounted on said slide, said tip cutting mechanism being movable into and out of 25 the support pockets with the movement of the slide, a shaft, a slidable sleeve thereon held against revolution independently of the shaft, said sleeve being arranged for sliding movement on the shaft with the movement 30 of the table, a slide operating cam on said sleeve, cutting and wrapping device operating cams on said sleeve, a table operating cam on the shaft arranged to move the table alternately with the movements of 35 40 the slide, and support operating means driven from said shaft.

6. In a cigarette tipping machine, a shaft, a continuously moving pocketed cigarette support, driven from said shaft, cigarette 45 tipping mechanism, a table carrying said tipping mechanism, a cam adapted to move certain portions of the tipping mechanism into the support pockets and maintain the same therein during the tipping operation, 50 tipping mechanism operating cams engageable by the tipping mechanism during engagement with the cigarette support, a cam on the shaft adapted to move said table and tipping mechanism thereon with the cigarette support during engagement of the tipping mechanism and support, retracting 55 means for the table operative between the engagements of the tipping mechanism and support, and driving means on the shaft 60 for the tipping mechanism moving and operating cams movable with the table.

7. In a cigarette tipping machine, a continuously moving cigarette support, a slotted slide movable perpendicular to the 65 support, a shaft passing through the slot

of said slide axially parallel with the direction of movement of said support, tipping mechanism mounted on the slide and movable into and out of engagement with the support by the movement of the slide, 70 a table movable in the same direction and at the same speed as the support, a guide thereon carrying the slide, a sleeve slidable but not revoluble on the shaft and movable with the table, a cam on said sleeve adapted 75 to move the slide toward and away from the cigarette support, tipping mechanism operating cams on said sleeve, tipping mechanism operating levers mounted on the slide and movable therewith into engagement 80 with their cams during engagement of the tipping mechanism and cigarette support, and a cam on the shaft adapted to move the table with the cigarette support during engagement of the tipping mechanism there- 85 with and to return the table to normal position between said engagements.

8. In a cigarette tipping machine, a cigarette support, means for feeding pasted tip material to said support, means for feeding 90 cigarettes onto the pasted tip material on said support, a bifurcated arm adapted to embrace the cigarette end, a slide arranged to move said arm into tip engaging position, an oscillating brush arm carried by the slide 95 adapted to wrap the tip ends successively around the cigarette, pins of unequal length on the bifurcations of said arm arranged to raise the tip ends successively into the path of the brush, and means for operating said 100 wrapping mechanism.

9. In a cigarette tipping machine, a cigarette support, means for feeding pasted tip material to said support, means for feeding 105 cigarettes onto the pasted tip material on said support, a bifurcated arm adapted to embrace the cigarette end, a slide arranged to move said arm into tip engaging position, an oscillating brush arm carried by the slide adapted to wrap the tip ends successively 110 around the cigarette, pins of unequal length on the bifurcations of said arm arranged to raise the tip ends successively into the path of the brush, means for operating said wrapping mechanism, means for continuously 115 moving the cigarette support, means for moving the wrapping mechanism with the support during the tipping operation, and means for returning the wrapping mechanism to its original position on the completion 120 of the wrapping operation.

10. In a cigarette tipping machine, a continuously operating cigarette support, and an independently operating tipping mechanism movable into and out of engagement 125 with the support.

11. In a cigarette tipping machine, a cigarette support traveling continuously in one direction, and a cigarette tipping mechanism traveling alternately in directions the same 130

as and contrary to said support, and movable laterally into engagement with the support while traveling in the same direction thereas.

5 12. In a cigarette tipping machine, a cigarette support operating continuously in one direction, a cigarette tipping mechanism reciprocatable in paths parallel to and perpendicular to the direction of movement of 10 the support and engageable with the support while moving in the same direction thereas.

13. In a cigarette tipping machine, a magazine, a carrying belt, a cigarette supporting belt, a continuous drive for said 15 belts, means for supplying pasted tip material to the supporting belt, a stationary cam in the path of cigarettes on the carrying belt arranged to project the same into engagement with the tip material on the supporting belt, and tip applying mechanism 20 movable into and out of engagement with the supporting belt.

14. In a cigarette tipping machine, a magazine, a carrying belt, a cigarette supporting belt, means for continuously driving 25 said belts, means for supplying pasted tip material to the surface of the tipping belt, a cam arranged to project the cigarettes from the carrying belt into engagement with 30 the tip material on the supporting belt, tipping mechanism including tip length cutting mechanism and means for applying the severed tip lengths to the cigarettes, movable independently of the supporting belt, 35 means for moving the tipping mechanisms into and out of engagement with the cig-

arettes on the supporting belt, and means for moving the tipping mechanisms with the supporting belt during the tipping operations and in the contrary direction between 40 tipping operations.

15. In a cigarette tipping machine, a magazine, a carrying belt having cigarette holding grooves, a cigarette support continuously operating parallel with the carrying belt having grooves registering with the grooves of the belt, pockets intermediate the grooves of said support, and tip length cutting and applying mechanisms mounted independently of the support, movable in part 50 into the pockets of said support in a transverse direction and subsequently movable parallel with the support.

16. In a cigarette tipping machine, a moving cigarette support, a tipping mechanism, 55 a slide carrying same, a table carrying the slide, tipping mechanism actuating means carried by the table, means for moving the slide and bringing the tipping mechanism into engagement with its actuating means, 60 and means for moving the table and mechanism thereon parallel with and in the same direction as the cigarette support during operation of the tipping mechanism, and for returning the table to original position after 65 the tipping operation.

In witness whereof I have hereunto set my hand in the presence of two witnesses.

JAMES CALLAGHAN.
